UNITED STATES PATENT OFFICE

CHARLES R. C. BORDEN, OF BOSTON, MASSACHUSETTS

VENTILATOR

Application filed March 1, 1930. Serial No. 432,291.

Interior ventilation and the arrest of air burdens of dust or like impurities have been problems augmented by urban developments.

Both private and public habitations within 5 the zone of heavy traffic have been acutely afflicted with the conflicting problems of ventilation and penetrating dirt. This is not only true on account of health and sanitation, but of practical importance on account of the 10 actual cost of daily service such as the preparation of rooms in hotels, apartments, hospitals and office buildings for occupancy and use. Such cleaning of dust, soot or other air carried deposit adds a very considerable 15 service cost which is well recognized as a factor in operating expense.

The inrushing air in any ventilating opening tends to concentrate the dirt carried thereby and the stronger the draft past the 20 ventilator the more dirt will be brought by the incoming air.

My invention contemplates the utilization 25 of the air velocity and its conversion from a difficulty into a factor of use. I accomplish this by providing the general deflection surface of a ventilator with deflections localized adjacent a dirt trapping aperture into which the particles of matter pass by resultant 30 forces while the air passes on without substantial retardation.

My invention is capable of embodiment in many forms. These vary considerably in appearance according to the material basis 35 of their construction.

By way of illustration I show a few characteristic types. These appear in the drawings as follows:

Fig. 1 is a general face view of one form of 40 my invention in partly detail.

Fig. 2 is a front view of a fragment of the deflector surface detailed.

Fig. 3 is a side section through such a ventilator in one of its various positions.

Fig. 4 indicates an installation showing a 45 central vertical disposition of the deflector surface.

Fig. 5 is a front view of a modification in fragment.

Fig. 6 a section through the same.

Fig. 7 is a face view in partial perspective of a further modification, and

Fig. 8 a section through the same.

Referring to Fig. 1, the structure there shown has for a general air or draft deflecting 55 surface a vertically or obliquely fluted face having ribs generally indicated at 1. In this form the ribs are angular in cross section preferably of 20° to 45° but undercut at successive transverse planes to form shoulders 60 10.

The ribs are cut back transversely on faces 11 to form a succession of pyramidal figures or serrations. These form notches 12 which taken in lateral pairs form resultant apertures which communicate with the chamber 2 enclosed by a backing 3 which constitutes a shallow box or chamber in which the dirt or deposit is collected.

Considering Figs. 1, 2 and 3 as a general 70 basis of operation it will be noted that the incoming air impinges on the deflecting surface and is generally urged upward. In this the generally upwardly deflected current is divided vertically by the ribs 1.

These divided currents pass across the faces 11 and encountering the shoulders 10 are 75 resultant deflected towards the apertures at 12. The air carried dirt particles having momentum follow lines of least resistance which are along the faces 11 and inclined shoulders 10 and enter the apertures formed by the notches 12.

They thus enter the chamber 2 which is 80 detachably mounted as at 13 on the face of the ventilator. The chamber 2 is substantially 85 a dead air chamber. The dirt passes into the box 4 and is collected there until such time as its removal is convenient.

Such ventilator traps may be variously installed and equipped. As shown in Fig. 3, a 90 drip trough 4 is preferably arranged at the sill edge 5, just inside the sash plane 6 the trough catching any rain or condensing moisture and also acting as a retainer for such dirt 95 as may fall from the sash above.

As shown in Fig. 4, the deflector may be 100 provided with lateral wings 7 so as to space it from the sides of the window casing and clear any side draperies as well as to close

the entire width of the window against inrush of air. As here shown the deflector may be vertically disposed, the facets being arranged to give the desired deflection of air draft as well as of incident dirt particles.

The serrated form shown in Figs. 1, 2 and 3 is of high efficiency but for the purposes of economy in production, I may dispose my baffle surfaces as transverse angular ribs having adjacent slots or openings, Figs. 5 to 8, by which the impinging dirt may be deflected and trapped in a rear compartment as 2 in Fig. 3. In such forms I provide vertical strips 23 which check and baffle any cross resultants or currents.

The general performance of draft and air currents and eddies is like that of the form first described.

Referring first to Figs. 5 and 6, the transversely disposed deflectors are shown as V-shaped members having lower faces 20 and upper faces 21. The dirt receiving apertures are intervening slots 22 into which the particles are deflected by the resultants of the air currents and the momentum of the dirt particles carried thereby and directed by the surfaces 20 and 21.

In the form shown in Figs. 7 and 8 which is simplified as in Figs. 5 and 6 for production purposes, the baffling which may be vertical or angular, is effected by the downwardly disposed surfaces 30 and the upwardly inclined faces 31. These surfaces are the opposite sides of a flange bent out from a strip 34 to overhang the intervening slot 32. These members may be made up in strip form and like those of Figs. 5 and 6 may be of stamped metal.

In the form shown in Figs. 5 and 6, the strips constituting the portions 20 and 21 are pierced by the vertically disposed strips 23 which constitute the lateral deflectors.

As shown in Figs. 7 and 8, the strips 34 enter slots in the vertical strips 33.

My invention contemplates the disposition of the general draft receiving surface in either vertical or inclined positions, the facets or sub-deflecting surfaces adjacent the dirt receiving apertures being formed at proper angles with reference to the incident air current so as to give a maximum resultant deflection of the dirt particles toward the apertures.

All such forms and varieties although differing in appearance are in accordance with the concept of my invention which I therefore claim as follows.

What I therefore claim and desire to secure by Letters Patent is:

1. A ventilating device comprising a hollow dirt receiver having an air deflecting surface adapted to be disposed in upward disposition at the ventilating opening, said surface having converging transverse faces and apertures therebetween and opening into

the hollow receiver, said surface also including horizontal downwardly faced surfaces resistant to the upward draft of the air.

2. A ventilating device comprising a hollow dirt receiver having an air deflecting surface adapted to be disposed in upward disposition at the ventilating opening, said surface having a series of pairs of narrow transverse faces converging towards an aperture opening into the hollow receiver, and said surface also including horizontal downwardly faced surfaces resistant to the upward draft of the air.

3. A ventilator comprising a hollow container adapted to be supported in a ventilating opening and having its outer surfaces comprised of a series of transverse angular ribs and apertures therebetween, said ribs having horizontal baffle surfaces angularly undercut to form a series of pyramidal serrations whereby the upward rush of the air is deflected and the dirt particles carried thereby thrown through said apertures into the container.

4. A ventilation device including a dirt receiver having an air deflecting surface, said surface comprising upwardly disposed laterally convergent angular faces, each consisting of a series of projections of pyramidal form having overhanging bases and of successive tooth formation, said surface having dirt receiving apertures disposed at the angles of the laterally receding faces.

5. A ventilating device including an air deflection surface comprising upwardly disposed dentitions of pyramidal section and overhanging in vertical progression and having dirt receiving apertures in the apices of the re-entrant angles thereof.

In testimony whereof I affix my signature.

CHARLES R. C. BORDEN.
